COIN SELECTOR

Samuel D. Polsen and Sven H. Nelson, Fairfield, Conn., assignors of one-half to Vivian Marie Nelson, Bridgeport, Conn., and one-fourth to Blanche H. Polsen and one-fourth to Mildred P. Nelson, both of Fairfield, Conn.

Application September 29, 1948, Serial No. 51,745

4 Claims. (Cl. 194—97)

1

This invention relates to new and useful improvements in coin selectors.

An object of the invention is to provide a coin selector including a load-and-fire mechanism for moving a coin against a part to operate the same and to move the coin past such part whereby when said load-and-fire mechanism is set in motion further movement of the coin toward and by the part is no longer under the control of the operator or the person who inserted the coin into the selector.

Another object is to provide a mechanism of the character described wherein an inserted coin moves toward operating position by gravity and including means to arrest downward movement of the coin just short of operating position to prevent the coin falling with appreciable force onto a switch or other part to be operated and said means, on manual manipulation, adapted to move such coin to and past such switch or other part through operation of the mentioned load-and-fire mechanism.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a sectional view taken along the plane of the line 1—1 of Fig. 2;

Fig. 2 is a front elevational view of a coin selector made in accordance with the invention;

Fig. 3 is a rear elevational view of the coin selector of the invention;

Fig. 4 is an isometric view of a spring means employed;

Fig. 5 is a similar view of an actuator employed;

Fig. 5a is a similar detail view of the lower portion of the inner side of the actuator strip;

Fig. 6 is a side elevational view of the spring of Fig. 4; and

Fig. 7 is a front elevational view of said spring in its fully extended position.

In the drawings, the coin selector illustrated is to a considerable extent a coin selector now in commercial use. Our invention is illustrated as incorporated in that particular coin selector although it is to be understood that our invention is not limited, except where so specified in the claims, to any of the particular structure illus-

2

trated. Thus, it will be understood that the drawings and the following description are for the purpose of making clear the principles of the invention and specifically disclosing one operative embodiment of the same.

Referring in detail to the drawings, at 10 is generally designated a body on which various devices in the way of coin checkers are mounted, as well as a part to be operated and all the various parts for bringing about such operation, all in accordance with the present invention. The body 10 comprises essentially a plate 11 having side flanges 12 carrying studs 13 used in or for the mounting of the body in a box-like frame or casing (not shown) as is customary in the art.

A gate-like part or member 14 is hingedly mounted as on a pin 15 and a coil spring 16, about said pin and anchored at its respective ends to the part 14 and the body 11, normally tends to 20 yieldingly dispose said gate-like part toward or against the upper portion of the body 11. An upper edge portion 17 of the gate 14 is inclined outwardly (see Fig. 1) providing a coin receiving slot 18 between the plate 11 and the gate 14. 25 Mounted in part on the gate 14 and in part on the upper portion of the plate 11 are various coin checking devices customary in the art. These devices extend along a path between the slot 18 and a slot 19, which latter is open at its lower end and its inner side (as will be more fully set forth) and defined by a depending portion 20 of a bracket 21 and a spaced parallel plate-like portion 22.

Mounted on the lower portion of the front side of the plate 11 is a housing piece 23 spaced from the plate 11. A wall-like portion 24 formed by off-setting the plate 23 intermediate its vertical edges and at an incline provides or constitutes a wall for a channel 25 through which a slug (in this specification and the following claims, a slug is considered any object other than a proper coin and a coin is considered any object which it is desired that the present mechanism shall respond to or which it is desired shall bring about operation of a means or device controlled by the present mechanism) inserted through the slot 18 will be discharged without setting into operation the means controlled by the present mechanism.

On the inserting of a coin, the latter strikes one arm of the pivoted checking device 26 and 50 rocking the latter in a clockwise direction brings its arm 27 into such position that if another coin or slug is inserted in the slot 18 it will pass straight down through the discharge slot 25 to be returned. The first inserted coin having 55 rocked the device 26 as indicated, moves between

an arm 28 of the device and a gauging pin 29 and along a path on a chute or shelf 30 and if perforated will be picked up by a checking device comprising a wire 31 and will be held against further movement. A coin passing this checking device moves along the chute 30 and under a magnet 32. If the coin or slug offered is magnetic, it will be retained by the magnet 32 but if it is a proper coin it will pass by the magnet and along a suitable path and will drop down to a position where it is arrested by engagement with the upper sides of arms 33 of a combined stop means and load-and-fire mechanism, later to be described.

As a coin rocks the device 26, a pivoted L-shaped lever 34 is rocked on its pivot 35 and shifts the wire checking device 31 to an out-of-the-way position to permit the edge of the coin to pass over the end of said wire. Then a second and counterweighted L-shaped lever 36 also on pivot 35 having been rocked, tends back to normal position and re-positions the wire checking device 31 to have its end enter the opening of a perforated coin and hold the latter. At 37 is a means, hinged at 38 and having a plate-like part 39 normally extending into a slot 40 in the gate 14. On any attempt to "stuff" the present device, the gate 14 will swing on the pivot pin 15 but a leaf spring 41 yieldingly holds the means 37 so that its part 39 prevents forcing of any slugs or the like by the checking wire 31.

When a slug has been stopped by any of the suggested checking mechanism, thereafter, on operation of a manual generally designated 42, a scavenger arm 43 is rocked about its pivot 44 to carry such slug from under the magnet or out of or off of the other checking mechanism and deliver such slug to the chute 25 cut of the bottom end of which it passes to be returned to the party who inserted it into the mechanism. The scavenger arm 43 is pivotally mounted on the upper portion of the body or plate 11 at the inner side of the gate 14.

The scavenger arm 43 includes a portion 45 through which projects a stud 46 carried by the manual 42 and passing freely through an opening 47 in the plate 11. Pivot 44 also passes through and is fixedly mounted by the plate 11 and this pivot also passes through an arcuate slot 48 in the manual 42. On depression of this manual, the stud 46 is moved and a sweeping clockwise motion is imparted to the arm 43 and any slug being held in the path of this arm will be swept along by it and discharged into the chute 25. The gate 14 being only yieldingly held in position by the spring 16, the gate may yield slightly to permit of this movement of the arm 43 and the ejection of any slug.

Assuming a coin to have passed the magnet 32, the coin drops edgewise onto an iron or steel pad 48 located between a lower portion of plate 11 and a smaller plate 49 mounted on and parallel with plate 11. Such coin then bounces across a space between plates 11 and 49 and rides down a chute—a wall—50 to the upper end of the slot 19 and comes to rest on the arms 33. If the "coin" is actually a slug and does not bounce across to the wall 50 as suggested, it falls on inclined lugs 51 and moves laterally through a hole or opening 52 in the plate 49 and onto a chute 53 between the outer side of plate 49 and the rear portion of the plate 23 and is discharged through the return chute 25. Under certain circumstances, later to be recited, a coin will be shifted through the hole or opening 52 and returned through chute 25.

The present selector includes a part which is moved and which is itself a control device for setting into operation other mechanisms not here shown. Such other or controlled mechanism 5 comprises no part of the invention and it may 10 comprise a vending machine or a dispensing apparatus, etc. In the present instance, the control described consists of a micro-switch 54 which when energized will close a circuit through relays or otherwise to any suitable operating, as vending or dispensing, mechanism or the like.

In circuit with such controlled mechanism is a solenoid 55, the core of which controls movement of a keeper 56 mounting a pin 57 which 15 projects through an opening 58 in the plate 11 into the plate of movement of a coin moving from the pad 48 toward the chute 50 for entrance to the coin discharge slot 19. Thus, when a machine controlled by the present mechanism is in 20 operation, the solenoid 55 is energized and the pin 57 prevents a second coin from moving from pad 48 to chute 50 and thence to the coin slot 19. Such second coin will be stopped by the pin 57 and land on the lugs 51 and then be shifted 25 through the hole 52 onto the chute 53 for return through the return chute 25. When the solenoid 55 is not energized, the pin 57 is in an out-of-the-way position and movement of the coin from pad 48 is to chute or slot 19 as first described.

From the above description it will be understood that 18 is the entrance slot for slugs as well as coins when slugs are offered the machine and that 25 is the discharge or return chute for slugs and 19 the discharge chute for good coins 30 which have been accepted by the various checking devices and have been used to operate the present control mechanism.

In these mechanisms, as previously constructed and used, the micro-switch 54 is closed 40 by the weight of the coin. This provides considerable difficulty in that a very light weight spring is involved since such spring must be actuated by the weight of the coin and when thin or worn coins are offered it is desired that they 45 be accepted and the mechanism respond to them. However, to accomplish this, an extremely light spring must be provided in the switch and this occasionally results in the contact points of the switch freezing together since the spring is not 50 of sufficient strength to always insure separation of such points once the contact has been made.

With the present mechanism, the coin is forcefully and mechanically moved against the switch manual to operate the latter and past the switch manual for discharge from the slot 19 to release 55 the switch manual. In this connection, it is to be understood that in the present instance the switch manual represents a movable part which is a controlled part and that the invention is not necessarily limited to use with a switch manual 60 since clearly it may be used to actuate some other control or operating part.

According to the present invention, a spring device generally designated 59 is mounted on the 65 inner side of the plate 11. This device is shown as bent up from a single piece of wire and includes an intermediate or connecting portion 60, the arms of which are bent to provide coil springs 61 and thereafter said arms extend downwardly 70 in substantially parallel relation as at 62 and then in the same plane are carried inwardly toward one another as at 63. Thereafter, the wires are bent to extend rearwardly in parallel relation as at 64 and then again are carried downwardly 75 and outwardly as at 65 and their free lower ends

are bent to extend inwardly in substantially parallel relation comprising the stop device 33 above referred to.

A clip 66 including a transversely U-shaped body portion has the bight of such portion secured against the rear side of the plate 11 as by screws or the like 67. A tongue 68 of the clip 66 bears against the connecting portion 60 of means 59 to secure the latter in place. The side arms 69 and 70 of the clip extend outwardly between the arm portions 62 of means 59. In this way, the means 59 is secured in position against the rear side of the plate 11.

The manual, generally designated 42, comprises a lever 71 which lies along the inner side of the upper edge of the plate 11 and is pivotally mounted as on a stud 72 carried by the plate and passing through an opening 73 in the rear end portion of the lever. This lever 71 which is provided with the above mentioned arcuate slot 48 is normally held in a substantially horizontal position as by a spring 74, one arm 75 of which bears against the underside of a plate-like portion 76 of the lever and the other arm 77 of which bears against the stud or pivot 44 for the scavenger arm 43. With this arrangement, the lever is normally kept in the position illustrated in Fig. 3 with the lower edge of the slot 48 against the stud 44 and the plate-like portion 76 and a head-like portion 78 of the lever horizontal.

This head-like portion 78 of the lever is slotted as at 79 and such slot receives the upper head-like portion 80 of a rigid strip or plunger 81. A screw 82 passes through openings 83 in the head-like portion 78 and traverses the slot 79 in which the head 80 of the strip 81 has been inserted and passes through an elongated opening or slot 84 in said head 80. The screw thus serves to secure the strip 81 to the lever 71 and a washer 85 under the head of the screw clamps a spring 86 to the lever head 78 but with a depending finger-like portion 87 of said spring against the inner side of the strip 81.

This strip is located at the rear side of the spring device 59 and bears against the rear sides or ends of the coil portions 61 of said spring device and is guided in vertical movements by being located between the arms 69 and 70 of the body of clip 66. On the inner side of the strip, at its lower end, is a cam-like lug 88 having a rounded underside and being flat and inclined across as at 89 on its upper side.

In the normal or retracted positions of the parts (see Fig. 3) this cam 88 projects into the space between the portions 63 of the spring device 59 just above the horizontal arm portions 64 of said spring device. This lug or cam is of a greater diameter or width than the normal distance between such arms 64.

When a coin is inserted into the slot 18 and passes through the various checking devices it is delivered on the upper sides of the arms 33 which at this time comprise an arresting device or stop. Such a coin will occupy the position suggested by the broken line at A in Fig. 3. It will be understood that the arms 33 completely arrest motion of the coin so that the same is not free to drop with any shock onto the operating part for the micro-switch 54. Here such micro-switch is shown as including a button 90 to be actuated by a spring arm 91, which arm comprises a movable part. It will be seen clearly from Fig. 3 that the arm 91 will be in the path of a straight downward movement of the coin from the position A.

A coin having been inserted as described and having moved to the position A, the operator next depresses the manual 42 rocking the lever 71 about the pivot 72. This results in a downward vertical movement of the plunger or strip 81 and the cam 88 of said strip rides against the inclined portions 63 of the spring device 59 and forces apart the legs of said device thereby moving the arms 33 outwardly away from one another. Such arms extend through slots 92 and 93 formed in alignment in both the plates 20 and 22. This will be clear from a comparison of Figs. 2 and 3.

As the arms are moved outwardly in the slots 92 and 93 it is in their extreme positions or to the extreme positions to which they may be moved by the cam 88 that the coin passes between such arms. At this time the coin will be in the broken line position B of Fig. 3 and the arms 33 will be in the extreme dotted line positions of that figure in the extreme outer ends of the slots 92 and 93. Instantly the cam has moved a distance to cause the arms 33 to be moved to their extreme open positions to permit a coin to pass between them, the upper flat or straight across and longitudinally inclined surface 89 of the cam 88 moves from under the arms or spring portions 64. This release of the legs of the spring device 59 permits of the legs snapping back toward one another or toward their normal positions.

As this occurs, the arms 33 strike the curved edge portions of the coin in portions thereof above the center of the coin with a squeezing or camming action, pressing or squeezing or squirming the coin downwardly. At this time, the coin may be approximately in the dotted line position C of Fig. 3 and the center of the coin will be about to pass the movable part 91 and the latter will be against the button 90 whereby the micro-switch 54 will be closed. In the position C of the coin, the arms 33 will be in the intermediate positions in which they are shown by dotted lines in Fig. 3.

From the foregoing it will be seen that I have provided a means to stop the coin or arrest movement of the coin along the path to the part 91 so that the coin cannot fall under the influence of gravity any considerable distance into engagement with the said part and thus there can be no shock or jolting of this part. Additionally, with my load-and-fire mechanism comprising essentially the spring device 59 and the manual 42, when the operator depresses the manual or moves the lever 71 about the pivot 72 the device 59 is opened to release the coin.

Once the coin is released the operator has no further control over it since at such time the straight portion 89 of the cam has passed the arms 64 of the spring device and the legs of the latter snap back toward one another. As they do this, they press against the upper curved edge portions of the coin and force the latter downwardly against and past the movable part 91 to close the micro-switch 54. The operator cannot balance any part so as to keep the coin in switch closing position. Once he has set the coin in motion to any such extent that the latter may operate the movable part (in this instance the switch manual 91) he has no further control over movement of the coin. Additionally, since the coin is mechanically forced against and past the part 91 of the switch manual, the switch may include relatively stiff spring means as there is ample power for closing the switch. There-

fore there is no occasion for using delicate springs or a delicate spring or spring mechanism such as would permit the switch contacts to become frozen together.

On release of the manual 42 following its manual depression about the pivot 72, the spring 74 returns the parts, including the strip or plunger 34, to their normal positions. As the spring 74 swings the lever 17 back toward horizontal position the said lever pulls the plunger or strip 34 up to its normal position, that being the full-line position of said part in Fig. 3. During upward movement of strip 34 the upper inclined surface 33 of the cam 32 strikes the curves where the arms 64 of the device 59 start rearwardly and the plunger flexes outwardly as the spring 86 yields. When the cam has passed the mentioned portions of device 59 the spring 86 flexes the strip 34 back to normal position with the cam 32 over the portions 64. Thus the strip or plunger and the cam are returned to their normal positions without spreading the legs of the device 59 so that if a second coin has entered the slot 18 and been deposited on the legs or stops 33, such coin will not be accidentally released.

Having thus set forth the nature of our invention, what we claim is:

1. In a coin selector, a body having a coin receiving slot toward its upper end, a controlling part movably mounted on the lower end portion of said body and movable relative thereto, means defining a path from said slot to said part and along which a coin may move by gravity from said slot to a position adjacent said part, a normally closed stop in said path between said slot and said part and adjacent to the latter and adapted to receive and support a coin moving in said path at a point between said slot and said part, said stop including a pair of substantially parallel arms extending transversely of the mentioned path of movement of the coin and normally so positioned relatively laterally as to be engaged by the leading edge of a coin moving along said path from said slot toward said part, said arms from their normal positions movable laterally away from one another to open relation to permit of a coin passing edgewise between them, spring means yieldingly maintaining said arms in their normal relation and adapted to snap them back to such relation when moved laterally outwardly therefrom and released, a manual including means adapted on movement in one direction to move said arms laterally outwardly from their normal positions to fully open positions and then suddenly release them for rapid movement back to their normal positions under the influence of said spring means, and said arms when at their fully open positions adapted to permit of edgewise movement of the previously stopped coin between them and as the arms return to normal positions under the influence of said spring means to engage the opposite portions of the trailing edge of the coin and cam said coin against and past said part to move the latter relative to said body.

2. The coin selector as in claim 1 wherein said arms and spring means are integral parts of the same length of wire bent inwardly of its ends to

provide said arms extending substantially at right angles to the body of the wire and also bent to provide an intermediate portion intermediate its ends and in spaced relation to said arms.

3. The coin selector as in claim 1 wherein said arms and spring means are portions of the same length of wire the latter being bent to provide a generally elongated U-shaped structure including an intermediate bight or connecting portion and side bars, and said side bars being each coiled upon itself adjacent said connecting portion and then extending substantially parallel and having their free end portions bent at substantially right angles to provide said arms.

4. In a coin selector, a body having a coin receiving slot toward its upper end, a controlling part movably mounted on the lower end portion of said body and movable relative thereto, means defining a path from said slot to said part and along which a coin may move by gravity from said slot to a position adjacent said part, a combined stop and coin impeller comprising a single length of wire, said wire being bent intermediate its ends to provide a generally elongated U-shaped structure including an intermediate bight or connecting portion and side bars, said side bars being each coiled upon itself adjacent said connecting portion to provide springs, said bars in spaced relation to said coils bent toward one another and then from one another to define a throat portion, said bars beyond said throat portion bent substantially at right angles to provide substantially parallel laterally spaced arms comprising the free end portions of the bars, said arms comprising a normally closed stop and located and extending across said path above said part and adapted to receive and support a coin moving in said path at a point above said part, a manual including a lug adapted on movement in one direction to enter said throat and spread said bars and thereby move said arms laterally outwardly from one another and immediately on fully opening of said arms to pass completely through said throat and suddenly release said bars for rapid movement of said arms back to their normal positions under the influence of said coils, and said arms when at fully open position adapted to permit of movement of the previously stopped coin edgewise therebetween and as the arms return to normal relation under the influence of said coils to engage the opposite edges of the coin above the center of the latter and cam said coin against and past said part to move the latter relative to the first mentioned body.
